TUNING ARRANGEMENT FOR WIRELESS RECEIVERS

Claude Langdon Richards, London, England, assignor to The Hartford National Bank and Trust Company, Hartford, Conn., as trustee

Application February 7, 1944, Serial No. 521,427
In Great Britain October 1, 1942

5 Claims. (Cl. 74—10)

This invention relates to tuning arrangements for wireless receivers and has for its object to provide a tuning arrangement the manipulation of which requires very little concentration on the part of the user, but nevertheless enables rapid tuning to a desired station. The invention is thus particularly well adapted for wireless receivers designed for use in motor cars.

With this object in view, the tuning arrangement according to the present invention comprises a member coupled with the main tuning condenser or other tuning device. The said member is mounted for translational movement as well as for rotational movement without translation, the coupling being such that the translation causes coarse tuning and the rotation causes fine tuning. The tuning member consists of a rod journaled in an arm so as to move therewith in a translatory movement, while being capable of independent rotation in its journals. The arm is associated with a plurality of retaining devices distributed (not necessarily uniformly) over the scale thus tending to hold the arm in any one of a corresponding number of positions providing a preliminary or coarse tuning.

In order that the invention may be more readily understood, reference is made to the accompanying drawings which show a preferred embodiment of the invention and in which,

Fig. 1 is a perspective view showing the tuning arrangement dissociated from the wireless receiver,

Fig. 2 is a fragmentary cross-section substantially along the line II—II of Fig. 1,

Fig. 3 is a diagrammatic side view of a wireless receiver incorporating the tuning arrangement of Figs. 1 and 2.

Referring first to Fig. 3, the cabinet or housing 30 accommodates a loudspeaker 31 and a receiving unit indicated purely schematically at 32. The receiving unit is tunable in the usual way, the shaft which is to be rotated for altering the tuning of the receiver is shown at 33. Usually this shaft constitutes or is connected with the shaft of the main tuning condenser of the receiver. However, any other form of tuning element for the receiver, such as variable inductance, may be employed. The invention is not to be regarded as limited to any particular type of receiver or tuning element therefor. Fixed to the shaft 33 is a pulley 34 which is connected by a cord 4 to the pulley 3 of the arrangement shown in greater detail in Figs. 1 and 2 and hereinafter more fully described. The pulley 3 is secured to a shaft 2 which is journaled in a bearing plate 35 rigidly secured to or forming a main frame element of the cabinet or housing 30. The shaft 2 passes freely through an arm 1 which is spaced from the bearing plate 35 by a washer or distance piece 36 which preferably constitutes an anti-

friction bearing facilitating pivotal movement of the arm 1 about the axis defined by the shaft 2.

Referring now more particularly to Figs. 1 and 2, the arm 1 is provided at opposite ends with upstanding lugs 6 and 7 in which a rod 5 is journaled. The forward end of the rod 5 projects from the cabinet 30 and carries a knob 8 to facilitate manipulation. Adjacent the shaft 2 the arm 1 is provided with an upstanding side plate 9 with inwardly turned ears at either end. Journaled in this plate 9 are two jockey pulleys 10, 11 around which passes a cord 13 the ends of which are wrapped around and anchored to the rod 5. The cord 13 also passes around a pulley 12 secured to the top of the shaft 2. The cord 13 is associated with the rod 5 in such manner that on rotating the latter in its journals one end of the cord is wound on the rod and the other end is correspondingly unwound. Thus the direction of rotation imparted to the pulley 12 by the cord 13 is determined by the direction in which the rod 5 is rotated in its journals 6, 7 by manipulation of the knob 8. If the knob 8 is held against rotation, the pulley 12 is likewise held stationary in relation to the arm 1.

Carried at the forward end of the arm 1, e. g. on the lug 7 is a pointer 14 which moves over a scale 15 provided on the cabinet 30 and serves to show the setting of the tuning.

To permit rapid setting of the arm 1 to one or more predetermined tuning positions, a bar 16 is mounted within the cabinet 30 above and extending transversely of the rod 5. This bar 16 is curved in form and has a centre of curvature coincident with the shaft 2. Adjustably secured to the bar 16 by bolts 20 passing through a slot 19 are notched plates 17, 18, hereinafter termed click plates. The click plate 17 is flat whereas the click plate 18 has a stepped end, so that two click plates can be secured at a closer spacing than corresponds to the width of the heads of the click plates. A closer spacing can be achieved by securing the click plates alternately on the upper and lower sides of the bar 16. Co-operating with the click-plates 17, 18 is a pin 25 carried on a lever 21 pivoted at 22 to the lug 7 on the arm 1 and urged by a spring 23 to impel the pin 25 into engagement with the click-plates 17, 18. A stop 24 on the lug 7 serves to limit the movement of the pin 25 towards the bar 16.

The arm 1 is preferably made from sheet metal, the bracket 9 for the jockey pulleys 10, 11, and the lugs 6 and 7 in which the rod 5 is journaled being formed by bending up portions of the sheet metal blank.

In the drawings, no means are shown for keeping the cords 4, 13 taut. Any conventional means may be provided for this purpose. In the case of the cord 13 one or both of the pulleys 10, 11

may be movably mounted and spring loaded so as to maintain the requisite tension in the cord.

The arrangement as described and illustrated operates in the following manner:

By means of the click mechanism (17, 18, 25) the rod 5 and arm 1 can be releasably detained in any one of a number of predetermined positions corresponding substantially to the tuning for selected transmitters. If the selected transmitter is not exactly in tune, fine tuning adjustment is effected by rotating the knob 8 while the arm 1 remains stationary in the position determined by the click mechanism. The engagement of the pin 25 in the click plates 17, 18 is sufficiently positive to prevent accidental disengagement, but is not such as to prevent the displacement of the arm 1 from one tuning position to another by the user.

I claim:

1. In a wireless receiver, a tunable element incorporated in the receiver, a shaft in driving connection with the tunable element, an arm pivotal about said shaft, a rod journaled on said arm for rotation about an axis at right angles to and intersecting the axis of the shaft, a pulley secured to the shaft, and a cord passing round the pulley with its ends wrapped round and anchored to the rod in such manner that rotation of the rod causes one end of the cord to be wound up on the rod and the other end to be unwound from the rod, whereby the shaft is held against rotation in relation to the arm except on rotation of the rod.

2. An apparatus for adjusting the position of a tunable element comprising, a driver member for the tunable element, an arm member, said driver member and said arm member being independently rotatable about a common axis, means to hold the arm member in predetermined positions about the axis of the said arm member corresponding to coarse adjustments of the tunable element, a rod member rotatable about its longitudinal axis, mounted on said arm member and rotatable about said common axis in synchronism with the arm member, and a coupling member fixedly positioning the arm and the driver member relative to each other upon rotation of the arm member, said coupling member interconnecting said rod member and driver member and producing rotation of the driver member relative to the arm upon rotation of the rod member about its said longitudinal axis corresponding to fine adjustment of the tunable element.

3. An apparatus for adjusting the position of a tunable element comprising, a driver member for the tunable element, an arm member, said driver member and said arm member being independently rotatable about a common axis, a stationary member fixed in relation to the axis and parallel to the plane of rotation of said driver and arm members, a plurality of plate members adjustably mounted on said stationary member, said plates each having a notch therein, means engaging said notches to hold the arm member in predetermined positions about the axis of the said arm member corresponding to coarse adjustments of the tunable element, a rod member rotatable about its longitudinal axis mounted on said arm member and rotatable about said common axis in synchronism with the arm member, and a coupling member fixedly positioning the arm and the driver member relative to each other upon rotation of the arm member, said coupling

member interconnecting said rod member and driver member and producing rotation of the driver member relative to the arm upon rotation of the rod member about its said longitudinal axis corresponding to fine adjustment of the tunable element.

4. An apparatus for adjusting the position of a tunable element comprising, a driver member for the tunable element, an arm member, said driver member and said arm member being independently rotatable about a common axis, a stationary member fixed in relation to the said axis and parallel to the plane of rotation of said driver and arm member, a plurality of plate members adjustably mounted on said stationary member, said plates each having a notch therein, detent means comprising a lever element secured to said arm member, a pin member mounted on said lever element and a spring member engaging said arm and said lever to urge the pin against said plate members and to engage the pin and the notches to thereby hold the arm in predetermined positions about the axis of the arm, said positions being fixed by the notches in said plates and corresponding to coarse adjustments of the tunable element, a rod member rotatable about its longitudinal axis, mounted on said arm member and rotatable about said common axis in synchronism with the arm member, and a coupling member fixedly positioning the arm and the driver member relative to each other upon rotation of the arm member, said coupling member interconnecting said rod member and driver member and producing rotation of the driver member relative to the arm upon rotation of the rod member about its said longitudinal axis corresponding to fine adjustment of the tunable element.

5. An apparatus for adjusting the position of a tunable element comprising, a driver member for the tunable element, an arm member in the form of a sheet metal stamping, integral bearing brackets at opposite ends of the arm member, said driver member and said arm member being independently rotatable about a common axis, a stationary member fixed in relation to the said axis and parallel to the plane of rotation of said driver and arm members, a plurality of plate members adjustably mounted on said stationary member, said plates each having a notch therein, means comprising a lever element secured to said arm member, a pin mounted on said lever element and a spring member engaging said arm and said lever to urge the pin against said plate members and to engage the pin and the notches to thereby hold the arm in predetermined positions about the axis of the rotatable arm member, said positions being fixed by the notches in said plates and corresponding to coarse adjustments of the tunable element, a rod member rotatable about its longitudinal axis mounted on said arm member in said brackets and rotatable about said common axis in synchronism with the arm member, and a coupling member fixedly positioning the arm and the driver member relative to each other upon rotation of the arm member, said coupling member interconnecting said rod member and driver member and producing rotation of the driver member relative to the arm upon rotation of the rod member about its said longitudinal axis corresponding to fine adjustment of the tunable element.
